REVOLVING SASH AND DOOR HOLDER

Hugo Steckling, Wausau, Wis.

Application July 29, 1949, Serial No. 107,531

1 Claim. (Cl. 144—288)

1

This invention relates to adjustable support devices, and more particularly to a device to be used for supporting doors, window sash, screen sash, and the like, during painting thereof.

A main object of the invention is to provide a novel and improved adjustable support device for holding a door, window sash, screen sash, or the like, in a desired position while being painted, said device being very simple in construction, easy to adjust, and allowing the object being painted to be rotated to any desired position in an expeditious manner.

A further object of the invention is to provide an improved adjustable support device for holding a window sash, door, or the like, during painting, said device being adjustable to secure different sizes of window sash or doors therein, the device being inexpensive to manufacture, sturdy in construction, and providing a great saving of time and labor in painting a door, window sash, screen sash, or the like.

Further objects and advantages of the invention will become apparent from the following description and claim, and from the accompanying drawings, wherein:

Figure 1 is a fragmentary front elevational view of an adjustable support device constructed in accordance with the present invention;

Figure 2 is a top plan view of the device of Figure 1;

Figure 3 is a fragmentary side elevational view of the support device of Figure 1, showing the adjustable supporting element for engaging the bottom edge of the object to be supported in the device;

Figure 4 is a cross-sectional detail view taken on line 4—4 of Figure 1;

Figure 5 is an enlarged cross-sectional detail view taken on line 5—5 of Figure 1;

Figure 6 is a cross-sectional detail view taken on line 6—6 of Figure 1;

Figure 7 is an enlarged fragmentary detail elevational view of the side marginal portion of one of the slidable clamp members employed in the support device of Figure 1;

Figure 8 is a fragmentary view similar to Figure 7, but showing the side marginal portion of the inner slidable clamp member employed in the support device of Figure 1.

Referring to the drawings, 11 designates a tripod structure comprising a pair of horizontal plate members 12 and 13, to which are secured the three downwardly-divergent and outwardly-bent identical supporting legs 14, the upper portions of the legs, shown at 15, extending through

2

the plate members 12 and 13 and preferably being welded thereto. Designated at 16 is a vertical sleeve member extending through and rigidly secured to the upper plate member 12 and being rigidly secured at its lower end to the lower plate member 13.

Designated at 17 is a vertical channel member secured by means of respective horizontal angle brackets 18 to the front marginal portions of plate members 12 and 13. As shown in Figures 1 and 6, the channel member 17 is provided with in-turned marginal flanges 19, 19, said flanges being slit adjacent the bottom end of the channel member and bent inwardly thereat to define inwardly-directed stop lugs 20, 20 at the bottom of said channel member. Slidably positioned in channel member 17 is a substantially rectangular vertical plate 21 having vertical marginal beads 22, 22 slidably received in the channel member 17 adjacent the flanges 19, the plate 21 having a metal pad element 23 secured thereto at its intermediate portion and located adjacent the main wall of the channel member shown at 24. Designated at 25 is a block member extending between the flanges 19, 19, and secured to the block member 25 by means of bolts 26 is a U-shaped strap bar 27, the bolts 26 passing through pad element 23, plate 21, block 25 and strap bar 27, as shown in Figure 5. Secured between the legs of strap bar 27 is a rectangular wooden block 28. Secured to the forward edge of block 28 is an upstanding vertical plate member 29. Designated at 30 is a clamping bolt extending through pad element 23, plate 21, block 25, bar 27, block 28 and plate member 29, said bolt being provided with an outer wing head 32. Disposed in a hexagonal recess in block 28 is a hexagonal nut 31 located inwardly of plate member 29 through which bolt 30 is threaded. When the bolt 30 is advanced inwardly, its inner end is engageable with the main wall 24 of the channel member 17 to frictionally lock the plate 21 with respect to said channel member by causing the beads 22 to engage the flanges 19 as well as by engagement of said inner end with said main wall. The block 28 may, therefore, be secured at a desired elevation with respect to the channel member 17, said block serving as a support for the lower edge of a window sash or the like to be supported for painting.

Telescopically received in the sleeve 16 is a tubular post member 33, the top end of the sleeve 16 being inwardly compressible, as by the provision of a slit 34 therein and being provided with a clamping band 35. Band 35 has end lugs 36

through which passes a clamping bolt 37, whereby the post member 33 may be clamped in the sleeve 16 in a vertically-adjusted position therein.

Designated at 38 and 39 are large disc members which are secured together and are bolted to a plate member 40. Extending centrally through the disc members 38 and 39, through plate member 40 and through the upper portion of post member 33 is a bolt 41 provided with a wing nut 42. The disc members 39, 38, may be clamped in a desired rotated position around the axis of bolt 41 by tightening the wing nut 42.

Secured to the disc member 39 is a rectangular vertical plate member 43. Secured to the outer face of plate member 43 at the side margins of said plate member are the respective pairs of blocks 44, 45 and 46, 47. Secured to the outer face of plate member 43 at the mid-portions thereof are the respective upper and lower blocks 48 and 49. Secured to said outer face between the blocks 48 and 49 is a nut member 50.

The upper blocks 44, 48 and 46 are formed adjacent plate member 43 with horizontally-aligned grooves, shown at 51, 52 and 53. The lower blocks 45, 49 and 47 are formed with similar horizontally-aligned grooves 54, 55 and 56. Designated at 57 is a first U-shaped clamping frame having top and bottom arms 58 and 59, respectively, slidably received in the aforementioned aligned grooves, as shown in Figure 1. Designated at 60 is a second U-shaped clamping frame having top and bottom arms 61 and 62 likewise slidably received in said grooves inwardly of the arms 58 and 59, the ends of the frames, shown respectively at 63 and 64 being located outwardly adjacent the respective sides of the plate member 43. The end of frame 57 is formed with a vertical upstanding flange 65 and the end of frame 60 is formed with a vertical upstanding flange 66. The flange 65 carries inwardly-projecting teeth 67 and the flange 66 carries inwardly-projecting teeth 68.

Rotatably carried by flange 65 is a threaded rod 69 extending threadedly through nut 50 and provided with a hand crank 70 outwardly adjacent the end 63 of frame 57. By rotating hand crank 70 the frame 57 may be moved toward or away from the nut 50. The inwardly-opposing edges of arms 61 and 62 of frame 60 are formed with spaced notches 71. Pivoted to the plate member 43 are respective dogs 72 and 73 engageable in said notches. Pivoted to dog 72 is a toggle arm 74 and connecting the intermediate portion of arm 74 and the intermediate portion of dog 73 is a link bar 75. From Figure 1 it will be seen that the dogs 72 and 73 may be locked in engagement with the notches 71 by rotating arm 74 clockwise past a dead center position with respect to link bar 75. The dogs may be disengaged from notches 71 by rotating arm 74 counterclockwise, as viewed in Figure 1.

In operation, a window sash or the like may be secured to the device by placing same between the flanges 65 and 66, the bottom edge thereof being supported, if so desired, on the block 28. The hand crank 70 is then rotated to move the frame 57 inwardly and to cause the sash to be

clamped between the teeth 68 and 67 of the clamping frames. Coarse adjustments for different widths may be made by engaging the dogs 72 and 73 in different notches of the arms 61 and 62 of frame 60.

The object to be painted may be rotated to any desired position by loosening wing nut 42, setting the object in the desired position, and then re-tightening said wing nut. Adjustments for height may be made by loosening wing nut 37.

The block 28 may be lowered after the object to be painted is clamped between the teeth 68 and 67 by loosening the wing screw 30 allowing the plate 21 to be moved downwardly in the channel member 17.

Although a specific embodiment of an adjustable support device for holding window sash, doors, or the like, while being painted, has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

An adjustable support device of the character described comprising a base, a vertical post member secured to said base, a vertical guide member secured to said base, a support element slidably mounted in said vertical guide member, means releasably locking said support element in said vertical guide member, a plate member rotatably secured to the upper portion of said post member, parallel inwardly-facing guide track elements carried by said plate member, a pair of opposing clamping frames slidably positioned in said guide track elements for longitudinal movement therealong, respective upstanding opposing jaw elements carried by the ends of said clamping frames, and means for adjustably securing said clamping frames with respect to the plate member, said last-named means comprising longitudinally-spaced notched portions formed in the arms of one of the clamping frames, respective dogs pivoted to the plate member and engageable in said notched portions, means for releasably locking the dogs in notch-engaging positions, a longitudinal shaft secured rotatably in the end of the other clamping frame and extending parallel to the guide track elements, a nut secured to the plate member threadedly receiving said shaft, and a crank handle carried by said shaft.

HUGO STECKLING.
